UNITED STATES PATENT OFFICE.

WILLIAM W. OLCOTT, OF BUFFALO, NEW YORK, ASSIGNOR TO CHARLES S. DAKIN, OF SAME PLACE.

BUCKLE.

SPECIFICATION forming part of Letters Patent No. 430,785, dated June 24, 1890.

Application filed January 27, 1890. Serial No. 338,222. (No model.)

To all whom it may concern:

Be it known that I, WILLIAM W. OLCOTT, a citizen of the United States, residing at Buffalo, in the county of Erie and State of New York, have invented a new and useful Improvement in Buckles, of which the following is a specification.

This invention relates more especially to the buckles which are employed for connecting the back straps of vests and pantaloons.

My invention has the object to produce a simple self-locking buckle which is kept in a locked position by the tension of the straps united by the buckle, and which is conveniently unlocked for adjusting or disconnecting the straps without requiring the pointed tongues to be seized, which practice is inconvenient and apt to injure the fingers.

In the accompanying drawings, Figure 1 is a top plan view of my improved buckle applied to the back straps of a vest or pair of pantaloons. Fig. 2 is a longitudinal section of the buckle connected to the straps. Fig. 3 is a similar view showing the tongues open in the position in which the detachable strap may be removed from the buckle. Fig. 4 is a front elevation of the buckle detached from the strap. Fig. 5 is a perspective view thereof.

Like letters of reference refer to like parts in the several figures.

A A represent the back straps of a vest or pair of pantaloons. The frame of the buckle is rectangular in form and composed of side bars $a a$ and raised end bars $a' a^2$.

35 b represents a tongue-plate or cross-bar pivoted at its ends to the side bars $a a$ of the buckle-frame about midway between the end bars, so as to leave loops or spaces between the tongue-bar and the end bars of the frame.

40 b' b' are the tongues or prongs projecting forwardly from the pivoted tongue-bar, and bearing with their points against the front end bar a^2 when in a closed position. The tongue-bar is pivoted to the buckle-frame by pins or journals formed at the ends of the bar and entering openings in the side bars of the buckle-frame.

45 c represents a loop arranged on the pivoted tongue-bar in rear of its pivot, and to which the end of one of the back straps is perma-

nently attached by sewing or other means, as represented in the drawings. The opposite back strap is passed through the space between the pivoted tongue-bar and the front end bar a^2 from the inner side of the buckle, 55 and is held in the same by the tongues which penetrate the strap. The free end of the strap is passed through the space or loop between the pivoted tongue-bar and the rear end bar a' , and is confined in the buckle against the 60 outer side of the other back strap by said end bar, as represented in Figs. 1 and 2. The tension of the back strap, which is attached to the loop c of the tongue-bar, tends to swing the loop outwardly, causing the tongues to be 65 moved inwardly toward the front end bar a^2 of the buckle-frame and holding their points firmly against the end bar.

To open or unlock the tongues and release the detachable strap, the thumb or finger is 70 placed underneath the rear end bar of the buckle-frame, as represented in Fig. 3, so as to move the rear portion of the buckle outwardly. This movement causes the front portion of the buckle-frame to move inwardly 75 away from the tongues, the tension on the straps holding the tongue-bar and tongues in a plane with the strap permanently attached to the buckle, while the buckle-frame swings upon the tongue-bar as a fulcrum. 80 The points of the tongues being separated from the adjacent end bar of the buckle-frame, the detachable strap is free to be stripped from the tongues and adjusted in the buckle or detached therefrom. The portion of the 85 buckle-frame in rear of the tongue-bar thus serves as a lever or thumb-piece, whereby the tongues are conveniently opened to release the detachable strap from the buckle without the necessity of seizing the pointed tongues 90 for this purpose, and it also acts as a keeper which retains the free end of the detachable strap against the inner strap and prevents the same from projecting when attached to the buckle.

95 I claim as my invention—

The combination, with the rectangular buckle-frame A, composed of vertical side bars a and horizontal end bars $a' a^2$, connecting said side bars, of a tongue-frame com- 100

posed of a cross-bar pivoted to the side bars of the buckle-frame between the two end bars thereof, and provided with tongues or prongs projecting forwardly from said cross-bar and bearing against the front end bar a^2 of the buckle-frame, and with a loop c , arranged in rear of the pivot of the cross-bar and in front of the rear end bar a' of the buckle-frame, the tongue-frame being inclosed by the rect-

angular buckle-frame, substantially as set forth.

Witness my hand this 21st day of January, 1890.

WILLIAM W. OLCOTT.
